Res. 197

E. Johnson & D. B. Cox Assignees of Joshua Brundall of Troy, N Y
Letters Patent No. 297. Dated July 2. 1850.

The Schedule referred to in these Letters Patent and making
part of the same

To all to whom these presents shall come:

Be it known
that I, Joshua Brundall, of Troy, in the County of Rensselaer,
and State of New York, have invented or produced a
new design of Cook Stove and I do hereby declare that
the following is a full and exact description of the
same, reference being had to the annexed drawings,
which make a part of this specification, in which
fig 1. is a side elevation and fig 2. a view of the front
plate of the stove.

My Stove is in the form of that known
as the "premium cook stove". The ornament consists of
stars situated in the centre of the doors and rays
issuing therefrom.

What I claim and desire to secure by
Letters Patent, is the design of Cook stove represented in
the annexed drawings.
